FLUID OPERATED JACK

Jean Mercier, Paris, France

Original application March 7, 1936, Serial No. 67,716, now Patent No. 2,163,982, dated June 27, 1939. Divided and this application April 15, 1939, Serial No. 268,034. In France March 11, 1935

11 Claims. (Cl. 254—124)

The present application is a division of my prior patent application Ser. No. 67,716, filed March 7, 1936, patented as Patent No. 2,163,982, June 27, 1939.

5 The object of the present invention is to provide a fluid operated jack system for the control of a retractable landing gear for an aircraft of the type including two arms hinged to each other in such manner and adapted either to be brought 10 in line with or to be folded so as to make any desired angle, at least equal to 90°, with each other, this system being simpler than those used for the same purpose up to the present time.

According to an essential feature of the present invention, the fluid operated jack, made of 15 two parts slideable with respect to each other, has one of said parts pivoted to one of said arms and the other part pivoted to the other arm, respectively.

20 Other features of the present invention will result from the following detailed description of some specific embodiments thereof.

A preferred embodiment of the present invention will be hereinafter described, with reference to the accompanying drawing, given merely by way of example, and in which the only figure is a diagrammatic elevational view of a control system for a retractable landing gear made according to the invention.

30 In this figure, reference numerals 33 and 34 respectively show the two arms pivoted to each other at 35. In the known manner, one of these arms is connected to the body of the airplane, while the other is connected to the wheel support 35 of the landing gear. In this way, when these two arms are in the position shown by the drawing, that is to say in line with each other, the landing gear is in operative position, whereas, when these two arms are folded with respect to each other, making an angle of at least 90° with each other, the landing gear is retracted, that is to say in inoperative position.

In the example shown by the drawing, the part 37, or body, of the jack is pivoted at 41 to arm 33, while the end of piston rod 36, which constitutes the other part of the jack is pivoted through a pin 39 in a longitudinal notch 42 provided in the lateral projection, or lug, 43, of branch 34.

40 It will be readily understood that, when said arms 33 and 34 are in line with each other (position shown in solid lines), the traction that can be effected by the jack in the direction indicated by arrow F has for its effect to bring arm 34 in 45 the position shown in dotted lines. A movement

of the jack in the opposite direction, indicated by arrow F', will serve to bring back the whole to the position shown in solid lines. At this time, a finger 38, rigid with pin 39 and piston rod 36, is in line with notch 40. Continuation of the 5 movement in the direction of arrow F' causes finger 38 to enter into notch 40, which ensures the locking of the system. In this movement, pin 39 moves in notch 42, provided in an extension 43 of arm 34.

10 While I have, in the above description, disclosed what I deem to be practical and efficient embodiments of the present invention, it should be well understood that I do not wish to be limited thereto as there might be changes made in 15 the arrangement, disposition, and form of the parts without departing from the principle of the present invention as comprehended within the scope of the accompanying claims.

What I claim is:

1. A structure which comprises, in combination, a jointed bar made of two elements pivoted to each other, a jack for controlling the folding of said bar wholly supported by said bar, including two parts slideable with respect to each other, 25 one of said parts of the jack being pivoted to one of said bar elements, and the other part of the jack being pivoted to the other bar element, and means, carried by one of said parts of the jack, for locking said bar elements with respect 30 to each other when they are located in line with each other.

2. In combination, a foldable strut made of two strut portions pivoted to each other about an axis transverse to said strut and adapted to come 35 in line with each other so that said strut is capable of supporting longitudinal axial stresses, and a jack made of two parts slideable with respect to each other and respectively pivoted to said strut portions for bringing them into and out 40 of aligned position.

3. In combination, a foldable strut made of two strut portions pivoted to each other, about an axis transverse to said strut, and adapted to come in line with each other so that said strut is capable of supporting longitudinal axial compression 45 stresses, and a jack made of two parts slideable with respect to each other and respectively pivoted to said strut portions for bringing them into and out of aligned position.

4. In combination, a foldable strut made of two strut portions pivoted to each other, about an axis transverse to said strut, and adapted to come in line with each other, said strut being adapted 50 to support longitudinal axial compression stresses, 55

and a jack made of two parts slideable in each other and respectively pivotally connected to said strut portions, for bringing said strut portions into and out of line with each other.

5. In combination, a foldable strut made of two strut portions pivoted to each other, about an axis transverse to said strut, and adapted to come in line with each other, said strut being adapted to support longitudinal axial compression stresses, 10 and a jack made of two parts slideable in each other and respectively pivotally connected to said strut portions, for bringing said strut portions into and out of line with each other, and means to lock the aligned strut portions with respect to 15 one another.

6. In combination, a foldable strut made of two strut portions pivoted to each other, about an axis transverse to said strut, and adapted to come in line with each other, said strut being adapted to 20 support longitudinal axial compression stresses, a jack made of two parts slideable in each other and respectively connected in a pivoting manner to said strut portions, for bringing said strut portions into and out of line with each other, and 25 means for automatically locking said strut portions with respect to each other upon their coming into line with each other.

7. In combination, a foldable strut made of two strut portions pivoted to each other, about an 30 axis transverse to said strut, and adapted to come in line with each other, said strut being adapted to support longitudinal axial compression stresses, a jack made of two parts slideable in each other and respectively pivotally connected to said strut 35 portions, for bringing said strut portions into and out of line with each other, and means for locking said strut portions with respect to each other, operative by said jack at the end of the relative movement of the parts thereof that brings said 40 strut portions into line with each other.

8. In a retractable landing gear for an airplane, adapted to connect the body of said airplane with wheels, the combination of a foldable strut made of two strut elements pivoted to each 45 other about an axis transverse to said strut, and

adapted to come in line with each other, said strut being interposed between said body and one of said wheels, so as to support longitudinal axial stresses, and a jack made of two parts slideable in each other and respectively pivotally connected to 5 said strut portions, for bringing said strut portions into and out of line with each other.

9. In a retractable landing gear for an airplane, adapted to connect the body of said airplane with wheels, the combination of a foldable strut made 10 of two strut portions pivoted to each other about an axis transverse to said strut, and adapted to come in line with each other, said strut being interposed between said body and one of said wheels, so as to support longitudinal axial 15 compression stresses, a jack made of two parts slideable in each other and respectively pivotally connected to said strut portions, for bringing said strut portions into and out of line with each other, and means for locking said strut portions 20 with respect to each other, operative by at least one of said jack parts at the end of the relative displacement thereof that brings said strut portions into line with each other.

10. In combination, a foldable strut comprising 25 two strut portions connected together end to end by a rule joint whereby when the strut portions are in alignment they are capable of supporting stresses applied along their longitudinal axis without breaking joint, and a jack made of two 30 parts slideable with respect to each other and respectively pivoted to said strut portions for bringing them into and out of alignment.

11. In combination, a foldable strut made of 35 two portions pivoted to each other end to end, the pivotal axis lying to one side of the longitudinal axis of the strut when the strut portions are in alignment, whereby the strut is capable by itself of supporting longitudinal axial stresses, and a 40 jack located adjacent the pivoted side of the strut and composed of two parts slideable with respect to each other and respectively pivoted to said strut portions for bringing them into and out of alignment.

JEAN MERCIER. 45
